(57) **CLAIM**

The ornamental design for a power injector, as shown and described.

DESCRIPTION

FIG. 1 is a front perspective view of a power injector of our new design;

FIG. 2 is a right view thereof;

FIG. 3 is a left view thereof;

FIG. 4 is a bottom view thereof;

FIG. 5 is a top view thereof;

FIG. 6 is a front view thereof; and,

FIG. 7 is a rear view thereof.

The broken lines in the drawings are included for the purpose of illustrating environmental structure and form no part of the claimed design.
